UNITED STATES PATENT OFFICE.

EGBERT T. BROWN, OF BUFFALO, NEW YORK, ASSIGNOR TO BUFFALO SPECIALTY COMPANY, OF BUFFALO, NEW YORK, A CORPORATION OF NEW YORK.

TOOL-HANDLE.

No. 861,498.

Specification of Letters Patent.

Patented July 30, 1907.

Application filed January 29, 1906. Serial No. 298,341.

To all whom it may concern:

Be it known that I, EGBERT T. BROWN, a citizen of the United States, residing at Buffalo, in the county of Erie and State of New York, have invented a new and 5 useful Improvement in Tool-Handles, of which the following is a specification.

This invention relates more particularly to the class of handles used in connection with tools having a socket for receiving the tapering shank of the handle, such as 10 socket-chisels.

The object of this invention is to provide a light, strong and inexpensive handle which cushions the tool blows received by the same, so as to protect the tool from injury and breakage.

15 In the accompanying drawing: Figure 1 is a side elevation of the improved handle. Fig. 2 is a sectional elevation thereof. Fig. 3 is a cross section in line 3—3, Fig. 1.

Similar letters of reference indicate corresponding 20 parts throughout the several views.

The handle may be of any suitable or ordinary shape and has the usual tapering shank A and the shoulder A' at the upper end of the shank.

The central or body portion B of the handle is made 25 of wood or similar material, while its shank A and the portion adjacent to the shank consist of superposed disks, washers or layers *a* of leather or similar fibrous material possessing sufficient resilience or elasticity to cushion the blows received by the handle and prevent 30 the injury to the tool liable to result from the use of a hard and rigid handle which transmits dead blows to the tool. The tip or upper end C of the handle is preferably composed of similar cushioning washers *c* in order to protect the wooden body section of the handle 35 from the blows of the mallet or hammer and prevent splitting thereof, but if desired, these washers may be omitted and the wooden section continued to the extreme top of the handle.

The leather washers *a*, *c* are firmly glued together under pressure, and the washers and the wooden section 40

B are centered and further united by a core-rod D secured by gluing or otherwise in an axial bore or opening *e* of the handle. This rod preferably extends from the extreme lower end of the shank to a point above the wooden section but short of the top washers or layers of 45 the tip C, so that the blows received by the tip are not transmitted directly through the rod, but only through the washers and the wooden section. For this purpose, the bore *e* extends a suitable distance above the upper end of the rod, as shown in Fig. 2.

The leather or fibrous washers forming the lower portion of the handle extend some distance above the shoulder A', so as to receive the thrust of the socket of the chisel or other tool, thus not only acting as a cushion but also protecting the lower end of the wooden section 50 and effectually preventing splitting of the same.

My improved handle, while possessing the desirable cushioning capacity above described, at the same time combines lightness with strength and durability and can be manufactured at comparatively small cost. 60

I claim as my invention:—

1. A chisel or other end-driven tool-handle having a tapering shank and a shoulder at the upper end of the shank, the body-portion of the handle being constructed of wood and its lower or shank portion consisting of a series of 65 superposed layers of leather extending from the lower end thereof to a point above said shoulder, substantially as set forth.

2. A chisel or other end-driven tool-handle comprising a wooden central section, a tip composed of superposed leather disks or layers, a tapering lower portion having a shoulder and composed of a series of similar superposed leather disks extending from the lower end thereof to a point above said shoulder, and a core-rod passing through 70 said lower portion and the wooden central section and extending into the tip but terminating short of its top, the bore of the handle extending beyond the upper end of said rod, substantially as set forth.

Witness my hand this 15th day of January, 1906.

EGBERT T. BROWN.
